UNITED STATES PATENT OFFICE.

DARIUS W. SHOLLENBERGER, OF MONTGOMERY, PENNSYLVANIA, ASSIGNOR TO
AMERICAN WOOD WORKING MACHINERY CO., OF ROCHESTER, NEW YORK, A
CORPORATION OF PENNSYLVANIA.

FEED-CONTROLLING DEVICE.

1,066,440.

Specification of Letters Patent.

Patented July 1, 1913.

Application filed June 13, 1912. Serial No. 703,558.

To all whom it may concern:

Be it known that I, DARIUS W. SHOLLENBERGER, a citizen of the United States, residing at Montgomery, county of Lycoming, 5 State of Pennsylvania, have invented certain Improvements in Feed-Controlling Devices, of which the following is a specification.

My invention relates to machines having 10 a feeding apparatus which it is required to stop and start frequently, and it consists more especially in a method of applying a binder pulley to a feed belt and automatically locking the binder in working position, 15 and also in unlocking it when required, by the same hand lever that operates the binder.

In the drawings accompanying this application, Figure 1 is a plan view of my invention shown applied to the frame of a 20 woodworking machine. Fig. 2 is an enlarged side elevation of the essential parts. Fig. 3 is a sectional plan of the same, and Fig. 4 is a front elevation at a right angle 25 to Fig. 2. Fig. 5 is a side elevation of the locking segment.

A, Figs. 1 and 2, indicates a machine frame of any required design, on which a driving countershaft B is boxed.

30 C is a feed pulley mounted on a cross shaft 2 through which the feed mechanism of the machine is operated.

D is a driving pulley on the countershaft B, from which the belt 3 and feed pulley C 35 are driven.

40 4 is a binder pulley revolving on suitable bearings on an arm 5, which is supported on a rock shaft E having bearings on the main frame A.

6 is a hand lever which is used to manipulate the binder and thereby stop and start the feed shaft 2 at will, and 7 is a corresponding lever located at or near the rear end of the machine and connected by a link 45 8 through a rock shaft 30 to an arm on the shaft E, whereby the control of the feed can be had at two points.

The above description relates to old and well known mechanism for operating the 50 feed works of machines of various types.

My invention relates to improvements hereinafter described.

The binder arm 5 is secured to a sleeve 10 which is fitted to swing loosely on the rock

shaft E. To this sleeve is also secured a 55 triangular arm 11 which is located contiguously to a segment 12 which in turn is rigidly attached to the main frame A. At the center of this segment the shaft E has a bearing and therefore the triangular arm 11 60 swings concentrically therewith. One or more notches 13, Fig. 2, are cut in the periphery of the segment and a pawl 14 drops by gravity or otherwise into them. The pawl 14 is pivoted at 35 to the arm 11 and is 65 therefore controlled by it. A spiral spring 15 is made to encircle the sleeve 10 at a point next to the triangular arm 11 and one projecting end 17 of this spring is bent to engage the edge of the said arm, while the 70 other end 18 hooks under the edge of the cross girt 16 of the main frame. Thus the spring 15 acts to lift the binder 4 from the feed belt through the arm 11 and sleeve 10, after the pawl 14 is unlocked as further de- 75 scribed.

20 is a cam arm secured rigidly to the extremity of the rock shaft E and therefore moves simultaneously with the hand lever 6. On this cam arm is a rounded projection 21 80 which acts on a lug or pin 22 secured to the pawl 14. When, therefore, the rock shaft E is oscillated by the hand lever 6, the cam 21 lifts the pawl out of the notch 13 and permits the triangular arm 11 to swing free, the 85 spring 15 thus coming into action on the arm 5 and lifting the binder from the belt.

For the purpose of limiting the free movement of the triangular arm 11, a slot 23, Figs. 2, 3 and 5, is cut through the segment 90 12 concentrically with the rock shaft E, and three pins or lugs 24, 25, 26 pass freely through the slot: Lugs 24 and 25 are secured to the cam arm 20, and the central lug 26 is secured to the triangular arm 11. There is 95 a clearance space between lugs 24 and 25 sufficient to permit the lever 6 to be moved over in the direction of the arrow, Fig. 2, before lug 25 comes in contact with 26, and thereby the pawl 14 is lifted by 100 means of the cam 21: This unlocks the binder, and the spring 15 being in tension lifts the binder and stops the feed shaft 2, by relieving the strain on the belt. When it is desired to throw on the binder 4 and start the 105 feed works, lever 6 is pulled in the direction opposite the arrow, Fig. 2, thus forcing lug 24 against 26, and pushing the triangular

arm and pawl over until the latter drops into the notch 13 and locks. Other notches 13 may be made on the periphery of the segment 12 to hold the arm 11 in different positions, but in practice I find it better to make the binder arm 5 adjustable circumferentially on the sleeve 10, by means of the set screws 27, Figs. 3 and 4, thereby enabling the operator to obtain the proper angular position for the binder arm for tightening the belt and also to adjust the action of the spring 15 when the binder pulley is in operative position.

It will be seen that by means of the subsidiary lever 7 and the connecting link 8, which latter is jointed to the cam arm 20 and to the lever, or to an arm on a rock shaft 30 common to both, that the same control of the binder arm 5 is available at the rear or at any convenient point on the machine frame, as is had through the lever 6. The spring 15 not only acts to relieve the pressure of the binder pulley on the belt, but also serves to keep lug 26 in contact with lug 24 when the pawl 14 is lifted by the movement of cam 21.

What I claim as my invention and desire to secure by Letters Patent, is as follows:

1. In a feed controlling device a feed belt and an adjustable binder pulley therefor, a rock shaft upon which the binder pulley is pivoted, a controlling lever fast to the rock shaft, means comprising an arm distinct from said controlling lever connected to said rock shaft, a device carried by said arm for locking the binder pulley in operating position, and means also secured to the rock shaft for unlocking and thereby stopping the feed substantially as set forth.
2. In a feed controlling device a feed belt, a binder pulley operating thereon, an arm supporting said pulley, a rock shaft supporting the arm, a controlling lever fast to the rock shaft, means for loosely connecting the controlling lever and the binder pulley arm, a coiled spring operating to lift the binder from the belt, and means for locking the binder arm in working position and unlocking the same at will.
3. In a feed controlling device, a feed belt,

a binder pulley operating thereon, a binder arm carrying the pulley at one extremity and pivoted upon a rock shaft at the other, a controlling lever fast to said rock shaft, a coiled spring encircling the rock shaft and acting to lift the binder pulley from the belt, a notched segment concentric with the rock shaft, a pawl and supporting means therefor, and means for locking and unlocking the pawl from the notched segment for the purposes set forth.

4. In a feed controlling device, a feed belt, a binder pulley operating thereon, means for holding the pulley on the belt, a pivoted arm carrying the binder pulley, a rock shaft and a controlling lever fast thereto, a sleeve fitted loosely upon said rock shaft and externally to the bore of the binder arm, a coiled spring encircling said sleeve and acting when released to lift the binder pulley from the belt for the purposes set forth.

5. In a feed controlling device a feed belt, a binder pulley operating thereon and a pivoted supporting arm, a rock shaft and a controlling lever fast thereto, a notched segment concentric to the rock shaft, a locking pawl, a pawl supporting arm connected directly to the binder arm, a pawl lifting arm fast upon the rock shaft, whereby the operator is enabled to start the feed works, lock the binder pulley in working position, unlock the same and lift the pulley from the feed belt by the use of one controlling lever.

6. In a feed controlling device a feed belt, a pivoted binder arm and its pulley, a rock shaft and a controlling lever fast thereto, a notched segment concentric to said rock shaft, a locking pawl and its supporting arm pivoted upon the rock shaft, said pawl arm having a lug thereon, a pawl lifting arm fast to the rock shaft, said lifting arm having lugs acting in conjunction with the lug on the pawl arm whereby a movement of the controlling lever first unlocks the pawl from the notch in the segment and then may lift the binder pulley and stop the feed.

DARIUS W. SHOLLENBERGER.
